UNITED STATES PATENT OFFICE.

WARREN E. ELLIS, OF HAVERHILL, MASSACHUSETTS, ASSIGNOR TO W. E. ELLIS COMPANY, A CORPORATION OF MASSACHUSETTS.

BOW-MAKING MACHINE.

1,127,605.

Specification of Letters Patent.

Patented Feb. 9, 1915.

Application filed March 16, 1912. Serial No. 684,165.

To all whom it may concern:

Be it known that I, WARREN E. ELLIS, a citizen of the United States, residing at Haverhill, in the county of Essex and State 5 of Massachusetts, have invented new and useful Improvements in Bow-Making Machines, of which the following is a specification.

This invention, which relates to apparatus 10 for making ornamental bows, is particularly intended to provide a simple and easily-operated machine adapted to facilitate the assembling and securing together of the parts of bows constructed substantially as set forth 15 in an application for U. S. Letters Patent filed by me on the 23rd day of August, 1911, Serial No. 645,681. Such a bow, as constructed for attachment to a slipper or the like, is of the flat type and comprises a 20 body portion made from a strip of ribbon or similar material having its ends folded under its central portion and inclosing a lining or stiffening piece if desired, an attaching strip applied to the under side of said 25 body portion, this strip being usually made of buckram, and a central band crossing the outer side of the body portion and having its ends folded in under the attaching strip, these parts being secured together by a 30 metallic plate or clip provided with prongs which are passed through said parts and clenched, and my present invention includes various features of construction and arrangement whereby the bow parts above referred to are brought together in proper relation to one another and united to form a 35 complete bow in such manner that but little skill or labor is required of the operator of the apparatus.

40 In particular, my apparatus includes a movable anvil which, during the formation of the bow, is located between the central band and the body portion of the bow, mechanism for attaching the metallic clip, 45 the prongs of which are turned and clenched by the anvil, and folding devices which hold the ends of the central band against the under side of the body portion of the bow during the attachment of the 50 clip, together with various other parts and mechanisms hereinafter described, the complete machine as preferably constructed being illustrated in the accompanying drawings, in which:—

55 Figure 1 is a front elevation of the ma-

chine; Fig. 2 is a side elevation of the principal parts of the same, drawn to a larger scale; Fig. 3 is a sectional plan view on the line 3—3 in Fig. 2; Fig. 4 is a similar view of a portion of Fig. 3, showing a completed bow in the machine; Fig. 5 is an enlarged sectional view on the line 5—5 in Fig. 2, showing the parts in position to drive the metallic clip; Figs. 6 and 7 are front and side views, respectively, of the 60 clip-driving mechanism in a modified form; and Fig. 8 shows another modified form of the clip-driving mechanism.

The principal working parts of the machine shown in the drawings are carried 70 by a table 1 which may conveniently stand upon a bench 1^a having beneath it a treadle hereinafter referred to, whereby certain parts of the machine are operated. Said table is provided on its upper face with a 75 transversely-extending groove 2 for the reception of folding and gripping devices hereinafter described and with a recess 3 extending rearwardly from its front edge and crossing the groove 2, within which recess the bow is held while its parts are secured together. At the rear of the recess 3 the table 1 is provided with bearings 4 in which is journaled a transversely-extending shaft 5 carrying a supporting head 6, to 80 which head is detachably secured a forwardly-extending anvil 7 having the form of a thin flat plate or strip, and also an adjustable rod 8 serving as a gage and provided on its front edge with a spring clip 8^a, said 85 rod being held in any desired position of adjustment by a thumb screw 8^b. The anvil 7 is thus capable of being raised and lowered with respect to the top of the table 1 and is 90 so located that when lowered it is supported 95 by the table and extends across the groove 2, in which are located sliding plates adapted to be operated by suitable means such as a disk 9 mounted beneath the table 1 on a vertical pivot 9^a and having an operating 100 handle 10, said disk being provided with two cam slots 11 and 12 which are diametrically opposite to each other and respectively receive pins 13 and 14 adjustably secured at their upper ends to the sliding 105 plates above referred to. These plates, which are shown at 15 and 16 respectively, are provided at their inner ends with opposed folding and gripping devices 17 and 18, which devices preferably consist of de- 110

tachable plates and are recessed at their free edges, if necessary, to receive the clip-driving hammer hereinafter described.

The head 6, together with the anvil 7 and rod 8 which it carries, is normally held a short distance above the table 1 by means of a spring 19, shown as secured at its lower end to a downwardly-extending fixed rod 20 and at its upper end to an arm 21 fixed to and extending rearwardly from the shaft 5, and said anvil is preferably provided on its under side with a thin metal strip 22 which is secured at its rear end to the anvil and extends forward in parallelism therewith at a short distance below the same, with its free end projecting somewhat beyond the free end of the anvil, by which construction there is provided a slot 23 adapted to receive one of the bow parts 24 as hereinafter explained.

The clip-attaching mechanism is carried by a standard 24 secured to and extending upward from the rear portion of the table 1 and thence forward to a point above but a little to one side of the anvil 7, where it is provided with vertical guides 25 in which a head 26 is adapted to slide. At its lower end the head 26 is provided with a laterally-extending portion 27 located over the anvil 7, and in said portion 27 is detachably secured, by means of a set screw 28, the shank 29 of a clip-driving hammer 30 which, in the construction shown in Figs. 2 and 5 has at its opposite sides a pair of vertically-sliding spring-pressed rods 31 carried by the part 27 and provided on their inner faces just above their lower ends with shallow recesses 32, while pins 33 passing through the reduced shanks of the rods 31 at their upper ends serve to limit their downward movement under the influence of their actuating springs 34. Vertical reciprocation of the head 26 is provided for by suitable means such as a link 37 connecting said head to a lever 38 which is fulcrumed at 39 on the standard 24 and is connected by another link 40 to a foot treadle 41 located beneath the bench 1.

In using the machine above described the operator first inserts the central band 42 of a bow into the slot 23 and adjusts it therein until its rear edge is in contact with stops 45 and 46 secured to the parts 17 and 18 respectively, and its ends overlie the folding and gripping devices 17 and 18, which devices at this time are separated to their full extent, corresponding to the position of the disk 9 and handle 10 shown in Fig. 3. The previously-folded body portion of the bow, shown at 43, with the attaching strip 44 applied to its under side, is then placed bottom side up on the top of the anvil 7, and its rear end is moved backward until it is arrested by the stop 8, where it is held by the spring clip 8. Said

body portion is then pressed downward, carrying the anvil with it, until the plate 22 rests in the bottom of the recess 3, and thereupon the handle 10 is moved to the left from the position shown in Fig. 3, the cam slots 11 and 12 being so shaped that the resulting movement of the disk 9 causes the folding and gripping devices 17 and 18 to approach each other, with the result that the central band 42 is drawn tightly around the body portion 43 and has its ends folded down upon the attaching strip 44, where said ends are firmly held during the clip-attaching operation. A soft-metal clip 36 having previously been placed against the bottom face of the hammer 30, where said clip is held by the location of its opposite edges in the recesses 32 and positioned by a stop plate 35 secured to the rear face of the hammer, the operator then exerts a quick downward pressure upon the treadle 41, whereby the head 26 is moved downward and the downwardly-extending prongs 36a of the clip 36 are driven by the hammer 30 through the subjacent parts of the bow until said prongs reach the anvil 7, which anvil is provided with grooves 47 adapted to turn the ends of said prongs and cause them to be clenched against the under side of the body portion of the bow behind the central band 42. The rods 31 yield under the force of the driving blow and release the clip 36, and the bow being thus completed the treadle 41 is released and the clip-driving mechanism is raised by means of a spring 47a. The handle 10 is then thrown to the right, withdrawing the folding and gripping devices 17 and 18 from over the bow, and thereupon the spring 19 elevates the anvil 7 and the bow resting upon it, said anvil being located between the body portion of the bow and its central band. The bow is now free to be withdrawn from the anvil by sliding the bow forward, and thereupon the parts are left in position for a repetition of the operation.

The machine above described is adapted for making bows of various sizes and shapes within reasonable limits by reason of the fact that the anvil 7 and the folding and gripping devices 17 and 18 may be readily removed and replaced by other like parts of different sizes and contours, and to the same end the plates 15 and 16 are made adjustable with respect to their operating pins 13 and 14, and the stops 45 and 46 are adjustable on the parts 17 and 18, as shown. The clip-driving hammer 30 is also made detachable, so that it can be readily replaced by another hammer suitable for driving a different form or size of clip: For example, in case a narrow clip is to be employed the form of hammer shown in Figs. 6 and 7 may be utilized, this hammer being constructed substantially as already described,

except that the rods 31^a are carried by the hammer 30^a itself, instead of being carried by the lower portion 27 of the sliding head 26, and are located considerably nearer together than they are in the case of the hammer 30. In Fig. 8 still another form of driving hammer is shown, wherein the clip carrier 48 has downwardly-extending jaws 51 adapted to receive a clip 52 having the form of an ordinary staple, and is arranged to slide on the hammer 50 against the action of a spring 49, thus providing for a relative movement of the hammer and clip carrier which will permit the former to pass downward between the prongs 51 to the lower ends of the same and thus effect the driving of the clip.

Various other modifications in the construction and arrangement of the various parts of the apparatus may be made without departing from my invention, as will be evident.

I claim as my invention:—

1. A bow-making machine comprising an anvil arranged to move freely upward and downward and provided on its upper side with a clenching surface and on its under side with means for holding the central band of a bow thereon, means for supporting the anvil in its lowered position, and means for holding the anvil in elevated position except when manually moved downward upon its support.

2. A bow-making machine comprising an anvil arranged to move upward and downward, means movable with the anvil for detachably holding the body of a bow upon the top of the same, means for supporting the anvil in its lowered position, and means constantly tending to elevate the anvil.

3. A bow-making machine comprising an anvil arranged to move upward and downward and provided on its upper and under sides with means for detachably holding parts of bows thereon in position to be assembled, means for supporting the anvil in its lowered position, and means for elevating the anvil.

4. A bow-making machine comprising a fixed support, an anvil arranged to move freely upward and downward over said support and to rest on the latter when in its lowered position, and a strip located on the under side of the anvil and connected thereto at its rear end so as to move therewith, said strip extending forward to a point adjacent to the front end of the anvil and providing a recess beneath the latter which is open laterally and forwardly.

5. A bow-making machine comprising an anvil arranged to move upward and downward and to have a bow formed upon it, means for supporting the anvil in its lowered position, and an adjustable gage mov-

able with the anvil and provided with means for detachably holding a bow on said anvil.

6. A bow-making machine comprising a pivotally-mounted carrying head, an anvil detachably secured thereto and extending forward therefrom, a strip carried by the anvil on its under side and extending forward beneath the same to a point adjacent to the free end thereof, thereby providing a recess adapted to hold the central band of a bow, an adjustable gage movable with the anvil for positioning the bow thereon in a lengthwise direction, said gage being provided with means for detachably holding the bow on the anvil, and means for supporting said anvil in its lowered position.

7. A bow-making machine comprising an anvil movable upward and downward, means for supporting the anvil in its lowered position, means for holding the anvil in elevated position except when manually moved downward upon its support, a pair of folding devices mounted to slide toward and away from the anvil on opposite sides of the latter, manually-operated means for moving said folding devices simultaneously in opposite directions, and means for driving a fastening device into a bow body resting on the anvil.

8. A bow-making machine comprising an anvil arranged to have a bow formed upon the same, a pair of folding devices mounted to slide toward and away from the anvil on opposite sides of the latter and provided with longitudinal slots, pins adjustably held in said slots, and means operating upon said pins for simultaneously moving the folding devices in opposite directions.

9. A bow-making machine comprising a pivotally-mounted anvil movable upward and downward and means for elevating the same, means for supporting the anvil in its lowered position, a pair of laterally-sliding plates located on opposite sides of the anvil and movable toward and away from the latter, folding members detachably secured to the inner edges of said plates, and adjustable means for positioning the parts of a bow with respect to said anvil and folding members.

10. A bow-making machine comprising an anvil adapted to have a bow formed around the same, a pair of plates movable toward and from the anvil on opposite sides of the latter, means for operating said plates, and folding and gripping members detachably secured to the inner edges of said plates, adjacent to the anvil, and arranged to extend over the latter, said parts being provided with adjustable devices for positioning the central band of a bow with respect to the length of the anvil.

11. A bow-making machine comprising

an anvil arranged to move upward and downward and means for elevating the same, means for supporting the anvil in its lowered position, means movable with the anvil for detachably holding the parts of a bow on its upper and under sides, a pair of folding members mounted to slide laterally toward and away from the sides of the anvil, means for operating said folding members, and means for driving a fastening device into the bow parts supported by the anvil when in its lowered position.

12. In a bow-making machine, the combination with an anvil of a clip-attaching mechanism comprising a hammer, means for reciprocating the same, and a pair of parallel spring-pressed pins located on opposite sides of the hammer and arranged to yield in the line of its driving stroke, said pins being normally held with their free ends projecting slightly beyond the driving face of the hammer and provided adjacent to the latter with opposed shallow recesses

to receive the edges of a flat clip and hold the same against said driving face. 25

13. A bow-making machine comprising an anvil arranged to move upward and downward and to have a bow formed upon the same, means for supporting the anvil in its lowered position, a pair of folding members movable toward and away from the anvil on opposite sides of the latter and provided with recesses in their opposed inner edges, means for operating said members, a clip-driving hammer arranged to enter the recesses in said folding members when closed together, and means for operating said hammer. 30 35

In testimony whereof, I have hereunto subscribed my name this fifteenth day of 40 March, 1912.

WARREN E. ELLIS.
